UNITED STATES PATENT OFFICE.

ELWOOD THORNE, OF MARLBOROUGH, PENNSYLVANIA.

MACHINE FOR MAKING WIRE FENCES.

SPECIFICATION forming part of Letters Patent No. 351,816, dated November 2, 1886.

Application filed April 14, 1886. Serial No. 198,875. (No model.)

To all whom it may concern:

Be it known that I, ELWOOD THORNE, a citizen of the United States, residing at Marlborough, in the county of Chester and State of Pennsylvania, have invented certain useful Improvements in Machines for Making Wire Fences; and I do hereby declare the following to be a full, clear, and exact description thereof.

This invention relates to improvements in machines for making combined slat and twisted-wire fences; and the objects of my improvements are, first, to simplify the construction and reduce the friction of this class of machines; secondly, to arrange the pressing and winding machinery so that they may be operated connectively or separately; thirdly, to provide a convenient spool-winding attachment. The construction and arrangement of the different parts will be hereinafter fully described, reference being had to the drawings, in which—

Figure 1 is a plan of the machine. Fig. 2 is a side elevation with a part of the frame-work broken away to more clearly show the operating machinery. Fig. 3 is an end view, in which a part of the spool-winding adjustment is omitted. Fig. 4 is a perspective view of the spool-winding arrangement. Fig. 5 is a perspective view of the winding-reel. Fig. 6 is a detailed perspective view of a part of the reel. Fig. 7 shows a part of the carrying-roller and its connection with the reel. Fig. 8 is an enlarged perspective view of the spool-frame. Fig. 9 is a view of one of the spools. Figs. 10 and 11 are enlarged views of carrying-roller attachments.

Similar letters of reference indicate similar parts throughout the several views.

A is a frame, of suitable form and material, to support and connect the different parts of the machine. The upright posts of frame A support beam C. Upon beam C are bolted all the journal-boxes f of the several spool-frames.

The spool-frames (more fully shown in Fig. 8) are each cast of one piece of metal, of which c c are the sides of the spool-holder, d d are the cross-arms at the front part, and b the journal-shaft. Upon the end of shaft b is mounted spur-wheel a. Journal b is constructed of such length as to properly support

the operating machinery on one side and the spool-holder on the other side of beam C, and is secured within journal-box f. Projections d d are made wide, and the angles formed between them and the front bar of frame C guide and twist the wires drawn from spools E.

E is the spool. It is removably fitted into the spool-frames. It has three flanges, as shown, to guard and separate the different strands of wire with which it is wound. There are two washer-like projections, h, on the ends of spool E, that bear against the sides c c of the spool-carrier and produce the tension. Bolt v holds the spool in position. Thumb-screw u on bolt v is for the purpose of increasing or diminishing the tension of the wire. Spools E are provided each with two recesses, o o, in the end, the purpose of which will be shown. Two wire-holes are made in the body of the spool at each division for the purpose of holding the ends of wires.

a a are a train of spur-wheels, mounted upon the spool-frames outside of beam C, for the purpose of rotating the spool-frames and twisting the wire. These wheels are of equal diameter, and are geared together in such manner with regard to the spool-frames as to present the sides and ends of adjacent spools to each other, as shown, in order to allow room to pass in revolving. Motion is communicated to the train of wheels from any suitable source.

F is a carrying or supporting roller, journaled in suitable bearings upon the top of frame A. The object of roller F is to support the slats in a proper position and press them into place between the wires when fed into the machine. On roller F, at suitably-located positions, are secured adjustable projections i i, and also on one end of roller F is fastened an adjustable gage or stop, j, against which the slats are thrust into the machine and uniformly fixed in the wires. Upon the front end of roller F is fastened lever k, as shown, for the purpose of operating the roller. The lower end of lever k projects beyond the side of the roller, and in operation comes in contact with and is stopped by adjustable stop x. Stop x is secured to the inside of frame A, and by its adjustment regulates the extent to which projections i i may be carried forward by the motion of lever k.

H is the reel upon which the finished fencing is wound. It is placed forward of and below the general level of the twisting machinery. Being mounted on the front end of the frame, 5 it requires no additional frame-work.

n n are the reel-flanges, one of which is formed upon ratchet-wheel p.

The winding-bar H is composed of two pieces, the smaller of which is a wedge partially fitting into a groove, deeper at one end, in the larger one, H, and, projecting above the ground surface, assists in the removal of bar H from the roll of fencing. The ends of bar H are fitted into and removably inclosed in reel-flanges 15 n n, as shown. The reel-flanges or reel-heads n n are provided with journals that fit into suitable boxes on each side of frame A. These boxes or bearings are constructed open at the front part to allow the reel to be easily removed. Ratchet-wheel p and its lever m and pawl r turn the reel forward to wind up the fence as it comes from the machine. Pawl t upon frame A engages with ratchet-wheel p also, and holds the reel from turning backward 25 when lever m is being operated. Lever m and carrying-roller F are connected by chain l or other suitable connection. Chain l passes over the top at the end of roller F, and is secured to it by an end bolt, the other end of 30 the chain being provided with a hook, by which it is connected with lever m by being inserted in one of a series of holes shown. The rotation of the reel is increased or diminished by changing the position of the hook. It is obvious 35 that when roller F is reciprocated by means of its lever k its motion will be communicated to lever m, thereby through pawl r to the winding-reel.

In Fig. 4, I is a wire-coil holder or wire-reel journaled on a stationary shaft on frame A. It is held in place and tension is produced upon the wire by burr z. On the end of the shaft g is the spool-winding shaft, which is journaled under beam C on a suitable box, e. 45 Shaft g is parallel to the spool-holder shafts b, and has a pinion, w, meshing into one of the spur-wheels a, and operated thereby. Pinion w has a plate cast to one side of it, with two projections or lugs, q q, for the purpose of fitting into recesses o o in the spool-heads. The outward extension of shaft g is suitably constructed to receive the spools E, which are held in place by burr y.

The operation of my machine is as follows: 55 One or more strands of wire having been wound on each end of the spools by the winding mechanism, consisting of reel I and winding-shaft g, actuated by means of crank S, the spools are inserted in the spool-frames c 60 c, and the wires are drawn out in front of the spool-frames in opposite angles formed by the front end of the spool-holder and the cross-

arms d d, attached thereto. The wires being further drawn out, and the ends of the wires from each spool having been twisted together, 65 and tension having been applied to the wire by tightening thumb-screws u, a slat is inserted into the openings between the wires. Lever k, which has been previously depressed or moved backward, is then pushed forward, 70 so as to bring projections i i in contact with the slat, pressing it tightly against the wires. The spool-frames are then caused to revolve, twisting the wires upon the slat any desirable number of turns. Lever k is again depressed, 75 and another slat is inserted between the wires resting upon carrying-roller F and against stop j, which uniformly fixes their position in the wires. Lever k is again pushed forward, forcing the second slat into position in the wires, 80 which are in their turn twisted tightly upon it, as before. This operation being repeated, the product passes to the winding-reel, to which it is attached. The manipulations of lever k communicates motion to the winding-reel, as has been described, and the manufactured fencing is wound thereon. When a roll or bundle large enough for convenient handling has been wound, by lifting the roll one or both ends of the reel can be drawn out of 90 their bearings, said bearings being constructed open at their front part, as shown. The winding-bar can then be drawn out of the roll.

Having thus described my invention, what I claim is—

1. In a fence-machine, a combined wire guiding and twisting spool-holder having a front bar with two cross-arms or projecting arms, d d, substantially as described.

2. In a fence-machine, a spool-frame having a single bearing and a front bar with projecting arms, spools E, secured within the spool-frame, and means for drawing the sides of the frame together to give the necessary tension on the spools, all substantially as and for the purpose set forth.

3. In a fence-machine, in combination with the spool-frames and twisting machinery, roller F, with adjustable projections, for the purpose of pressing the slats into the wires, and an adjustable stop to fix the position of the slats in the wires.

4. In a fence-machine, the combination, with the twisting and adjusting mechanism, of the winding-reel, consisting of bar H, reel-heads n n, ratchet p, lever m, and pawls r and t, connected with carrying and pressing roller F, as and for the purpose set forth.

In testimony whereof I have hereunto set my hand this 8th day of April, 1886.

ELWOOD THORNE.
